H. LICHTE

CLEANING DEVICE FOR FILM STRIPS

Filed April 20, 1922

FIG. 2.

Patented Dec. 16, 1924.

1,519,460

UNITED STATES PATENT OFFICE.

HEINRICH LICHTE, OF BERLIN, GERMANY, ASSIGNOR TO DURA FILM PROTECTOR CO.,
OF NEW YORK, N. Y., A CORPORATION OF NEW YORK.

CLEANING DEVICE FOR FILM STRIPS.

Application filed April 20, 1922. Serial No. 555,711.

To all whom it may concern:

Be it known that I, HEINRICH LICHTE, a citizen of the German Republic, and a resident of Berlin, Germany, have invented certain new and useful Improvements in Cleaning Devices for Film Strips, of which the following is a specification.

It is a known phenomenon with film bands that after comparatively long use, and owing to dirt, as well as to slight damages, disturbing effects are perceived when the pictures of such a film are projected on the screen; the pictures looking as if the film band had been marred or spoiled by rain. It has already been proposed to clean the film band by benzine or the like, and also special devices have been constructed in order to clean the film band in a mechanical way. There are cleaning devices in which the film is conducted through the washing liquid and afterwards rubbed on both sides by brushes, and there are other forms of construction, in which the brushes dip into the washing liquid and the film passes between them. But neither of these devices has proved sufficiently effective, because the mere rinsing in the washing liquid or the simple brushing of the moistened films does not suffice to completely remove the dirt from the film band, and, furthermore, fine rents and similar or other unevenesses and irregularities which have arisen upon the rear side of the film are not in the least done away with. Also after having been treated in such a device the film still looks more or less as if marred or spoiled by rain, although the coarsest defects are, in fact, removed.

The present invention obviates the above-mentioned drawbacks in the following manner: Firstly, the film band is thoroughly brushed while being submerged in the washing liquid. Owing to the brushes working in the liquid, the brushed portions of the film are subjected to the double action of the brushes and the liquid and are constantly acted on by other parts of the latter, so that a very thorough cleaning is obtained. This may be rendered still better by letting the brush or brushes act repeatedly upon the film. Then, to remove even the very last remainder of dirt, the film band is subjected, at the side having the picture-carrying layer, to a strong jet of the same or another kind of washing liquid, and after this

treatment, it is again made to pass through between brushes which remove the superfluous liquid. Finally, the rear side of the film band is subjected to the action of a polishing means, such, for instance, as a cloth mop or the like, whereby rents and other unevenesses and irregularities are completely removed. The thus treated film appears as entirely cleaned and may be employed like a new one.

In order to make my invention more clear, I refer to the accompanying drawing, in which similar reference numerals denote similar parts throughout the several views and in which Figure 1 is a front view, with the middle portion in vertical section; and Figure 2 is a vertical transverse section through the middle portion of Figure 1, drawn on a larger scale.

The whole arrangement and combination of parts is supported by a table 1 to which are affixed two standards or frames 12 which may be stiffened relatively to one another. One of these frames carries a roll 2 upon which the film band to be cleaned is wound, and the other frame carries a similar roll 3 upon which the film is being wound after the cleaning operation is finished. The film band is indicated in the figures by a dot-and-dash line 4 and Figure 1 shows its path through the apparatus from the roll 2 to the roll 3.

From the roll 2 the film band passes downwards over guide rolls 5, 6 and 7 to rotary brushes 8 and 9, then further downwards and again upwards over a guide roll 10 to an upper guide roll 15. On its way from roll 10 to roll 15 the film band passes through between a lower pair of rotary brushes 9 and 11 and between an upper pair of rotary brushes 13 and 14. The upper guide roll 15 has teeth corresponding to the perforations of the film band. The film is now led over two small guide rolls 16 and 17 to a larger guide roll 18, by which it is brought into contact with a rotary mop 19; then and finally the film gets to the winding up roll 3.

The rotary brushes 8, 9, 11, 13, 14 are supported by a frame 20 which is connected at its upper portion with the frames 12, and the lower portion of which dips into the liquid in a receptacle 21. 22 are upwardly bent arms affixed to the frame 20 and assisting in supporting the rotary brushes. The recep-

tacle 21 is filled to about one half with the washing liquid, preferably tetrachloride of carbon, but also another fat-dissolving liquid may be employed. At any rate, the 5 receptacle is filled to such an extent that the lower brushes 8, 9, 11 are submerged in the liquid.

Within the receptacle 21 is a pump 23 which is also secured to the frame 20, sucks 10 washing liquid out of said receptacle through a filter 44, and ejects it through a mouth piece 24 against the film band portion which has just emerged from the body of liquid contained in the said receptacle. 15 The rotary parts of the device are rotated by a motor 25 which drives by means of a belt 26 a pulley 27 affixed to the shaft of the mop 19. The same shaft has affixed to it a pulley 27' which drives by means of 20 a belt 28 (indicated by dot-and-dash lines) a pulley 29 (Fig. 2). To the shaft of this pulley is affixed a cog-wheel 30 which meshes with a cog-wheel 31 secured to the spindle of the guide-roll 15. The change of 25 speed from the pulley 27' to the pulley 29 is preferably in the ratio 1:4, so that the number of revolutions of said latter pulley is only about one fourth of that of said other pulley. The speed of the guide roll 15 30 is considerably lower still by reason of the different diameters or circumferences of the cog-wheels 30 and 31.

The shaft to which the pulley 29 and the cog-wheel 30 are affixed supports also a 35 chain wheel 32 (Fig. 2) and chain wheels 33, 34, 35, 36, 37 and 38 of the same size are secured to the axles or spindles of the five rotary brushes, as well as to the driving shaft of the pump 23. All these chain 40 wheels are connected with each other by an endless chain also indicated by a dash-and-dot line in Fig. 1. The direction of motion is indicated by arrows.

Thus, the mop 19 is driven directly by 45 the motor; the rotary brushes are driven with but one fourth of the number of revolutions of the mop because of the gearing 27', 29, and the guide-roll 15 is rotated at a still lower speed by the mediation of the 50 gearing 30/31.

The receptacle 21 is guided by means of eyes 40 at two rods 39 which are affixed to the table, and it is provided with a cover 41 which is firmly secured to the frame 20. 55 The receptacle may be connected with this frame in any convenient manner, and after these parts have been disconnected the receptacle with its cover may be moved along the guide rods in downward direction until 60 it reaches the position indicated by a dot-and-dash line in Fig. 1. The parts located within the receptacle are then free for inspection and may be cleaned or repaired, and also another film band which is to be 65 cleaned may then be inserted. At the lower

end of the receptacle is an outlet-cock 42 through which the liquid may be discharged, and said receptacle is, furthermore, provided with a liquid-gauge 43 which permits of ascertaining the height of the 70 level of the liquid contained in the said receptacle.

The manner of operation of the apparatus is as follows:

The receptacle 21 having been so adjusted 75 that it assumes the position indicated by the dot-and-dash line in Fig. 1, the film wound upon the roll 2 is drawn over and around the guide rolls 5, 6, 7, 10, 15, 16, 17, 18, to the roll 3. Then the receptacle is lifted 80 into its working position and the motor is started. The rolls 5 and 15 now pull the film band slowly through the apparatus so that it is slowly wound off the roll 2 and slowly wound upon the roll 3 which is appropriately rotated by any suitable means. The film first dips into the cleaning liquid 85 and is cleaned in it firstly by the brushes 8 and 9 and then by the brushes 9 and 11. Owing to the cleaning being effected within 90 the liquid, and the film coming constantly in contact with other parts of the same, the cleaning is very thorough. The film, having thus been treated, leaves the liquid and its layer-bearing surface or side is then exposed to the action of the jet-pipe 24 which throws a strong jet of the cleaning liquid 95 against and upon it so that dirt-particles that, perhaps, still adhere to the film are washed away. The thus treated film portions then pass through between the brushes 100 13 and 14 which remove the adhering liquid, and after this the film passes in nearly dry state through the cover 41 and is exposed to the mop 19 which polishes its rear side 105 or surface whereby the eventually existing fine rents and the like are removed. The now finished film is, finally, wound upon the roll 3 and then removed from the apparatus together with this roll.

It is a matter of course, that the construction is not restricted to the exact number of rotary brushes and the other cleaning means as shown and described and also the relative arrangement of these parts may vary without departing from the gist of the invention.

Having now described my invention, what I claim as new and desire to secure by Letters Patent of the United States is:

1. Film-cleaning apparatus, comprising a main frame; a receptacle attached thereto to contain cleaning liquid; an auxiliary frame attached to the main frame and extending into said receptacle; upper and lower pairs of coacting rotary cleaning elements carried by the auxiliary frame and disposed within said receptacle, the lower pair being submersible in the cleaning liquid; film-feeding means; means for guid-

ing the film through said receptacle and between the coacting cleaning elements; and means for rotating all of the cleaning elements in unison.

5. 2. Film-cleaning apparatus, comprising a main frame; a receptacle attached thereto to contain cleaning liquid; an auxiliary frame attached to the main frame and extending into said receptacle; a set of three 10 horizontally-arranged, rotary cleaning elements mounted on the lower portion of the auxiliary frame to be submerged in the cleaning liquid, the central cleaning element contacting with both end elements; a pair 15 of coacting rotary cleaning elements mounted on the upper portion of the auxiliary frame; film-feeding means; means for guiding the film downwardly through the receptacle between the central cleaning element 20 and one of the end elements, and then upwardly through the receptacle first between said central element and the other end element and subsequently between the upper pair of cleaning elements; and means for 25 rotating all of the cleaning elements in unison.

3. Film-cleaning apparatus, comprising a main frame; a receptacle connected thereto and adapted to contain cleaning liquid; an auxiliary frame connected to the main frame and extending downward directly in line 30 with the receptacle, said receptacle and auxiliary frame constituting companion parts, one of which is movable vertically in 35 opposite directions with relation to the other to project the auxiliary frame into, and to withdraw it from, the receptacle; means for feeding film into and through said receptacle; rotary cleaning elements 40 carried by the auxiliary frame, certain of said elements being submersible in the cleaning liquid; a pump attached to said auxiliary frame above the submersible cleaning elements and communicating at its inlet side 45 with the liquid in said receptacle to draw in the same; and a mouth-piece in communication with the outlet side of the pump for spraying the emulsion side of the film after the latter has emerged from the 50 liquid.

4. Film-cleaning apparatus, comprising a main frame; a receptacle connected thereto and adapted to contain cleaning liquid; an auxiliary frame connected to the main frame

and extending downward directly in line 55 with the receptacle; means for feeding film into and through said receptacle; and rotary cleaning elements carried by the auxiliary frame, certain of which are submersible in the cleaning liquid; said receptacle and frame constituting companion parts, one of 60 which is movable vertically in opposite directions with relation to the other to project the auxiliary frame and its cleaning elements into the receptacle and to withdraw 65 them therefrom.

5. Film-cleaning apparatus, comprising a main frame; a receptacle adjustably connected thereto and adapted to contain cleaning liquid; an auxiliary frame connected to 70 the main frame and extending downward into said receptacle; rotary cleaning elements carried by the auxiliary frame, certain of said elements being submersible in the cleaning liquid; means for feeding film 75 into and through said receptacle; a pump attached to said auxiliary frame above the submersible cleaning elements and communicating at its inlet side with the liquid in 80 said receptacle to draw in the same; and a mouth-piece in communication with the outlet side of the pump for spraying the emulsion side of the film after the latter has emerged from the liquid; said receptacle being movable vertically with relation to 85 the auxiliary frame to withdraw the submersible elements from the receptacle and expose them for cleaning purposes.

6. Film-cleaning apparatus, comprising a main frame; a receptacle adjustably connected thereto and adapted to contain cleaning liquid; an auxiliary frame connected to the main frame and extending downward into said receptacle; rotary cleaning elements carried by the auxiliary frame, certain 90 of said elements being submersible in the cleaning liquid; film-feeding means; and means for guiding the film through said receptacle; said receptacle being movable vertically with relation to the auxiliary 95 frame to withdraw the latter and the cleaning elements carried thereby from the receptacle and expose them for cleaning or repairing.

In testimony whereof I have affixed my 105 signature.

HEINRICH LICHTE.
